WALL-MOUNTED TISSUE DISPENSER

Leslie R. Stewart, Haskell Road, R.D. 1,
North East, Pa. 16428

Filed May 9, 1968, Ser. No. 11,868

Term of patent 14 years

Int. Cl. D6—01

U.S. Cl. D52—2

FIG. 1

FIG. 2

FIG. 3

FIG. 1 is a front view of the holder for tissue box according to the invention.

FIG. 2 is a side view of the holder shown in FIG. 1.
FIG. 3 is a front view of the tissue holder.

The design is characterized by the combination of a rectangular case in association with a towel bar supported at the point of the diarcuate curves along the side panels, all as shown.

I claim:

The ornamental design for a wall-mounted tissue dispenser, as shown and described.
